UNITED STATES PATENT OFFICE.

WILLIAM O. HOUSTON, OF BELLAIRE, OHIO.

GAS-PRODUCER FOR FURNACES.

1,149,056.

Specification of Letters Patent. Patented Aug. 3, 1915.

Application filed February 9, 1914. Serial No. 817,384.

To all whom it may concern:

Be it known that I, WILLIAM O. HOUSTON, a citizen of the United States of America, and resident of Bellaire, county of Belmont, 5 and State of Ohio, have invented certain new and useful Improvements in Gas-Producers for Furnaces, of which the following is a specification.

This invention relates broadly to furnaces, 10 and specifically to a producer wherein gases are generated and directed to a combustion chamber.

The primary object of the invention is to provide a furnace of the gas-producer type 15 which is of simple construction and which has a pair of fire-boxes arranged side by side, both in open communication with the combustion chamber, and which are separately fired, thus assuring a constant production of gas in such quantities as will prevent any serious reductions in the temperature of the heating chamber.

As is well known, when gas is furnished 20 to the combustion chamber from a single fire-box, constant care must be exercised to keep the fuel bed in good gas-producing condition, and inattention frequently results in the fuel becoming packed and the fire smothered, retarding the production of gas 25 to such an extent that the temperature of the heating chamber is materially lowered, oftentimes with seriously detrimental results, particularly in furnaces of a muffle type wherein a substantially uniform temperature 30 is required.

It is therefore the purpose of the present invention to provide a furnace whereby the above recited objection is obviated and the possibility of an undue lowering of the temperature 35 is reduced to a minimum.

The invention resides in the features of construction, arrangement of parts and combination of elements which will hereinafter be fully described, reference being had to 40 the accompanying drawing, forming a part of this specification, in which—

Figure 1 is a longitudinal section of the invention; and Fig. 2 is a view partially in front elevation and partially in transverse 45 section on the line 2—2, Fig. 1.

Referring to said drawings, in which like designating characters distinguish like parts throughout the several views—1 1 indicate

the opposite side-walls, 2 the rear end wall, and 3 the crown of a gas producer which is 55 divided longitudinally by a central wall 4 to form two separate fire-boxes 5, both of which communicate through a passage 6 with a passage 7 leading to the combustion chamber (not shown). A set of grate-bars 60 8 provided in each fire-box supports the fuel-bed therefor, and said fire-boxes are fed separately, as from suitably arranged hoppers 9, or in any other suitable manner. Neither fire-box having any direct connection 65 with the other, each must be attended separately, and each furnishes its quota of the gas required for maintaining the furnace at a proper high temperature. As will be understood, it is highly improbable that the 70 fires in both fire-boxes would in any case become clogged or rendered inefficient at the same time. Thus, when the fire in one of said fire-boxes dies down from any cause, the other fire will be in condition to furnish 75 a sufficient volume of gas to maintain a relatively high temperature in the heating chamber of the furnace, and will, particularly if accelerated somewhat, supply gas 80 in ample volume to maintain the required 85 temperature until the fire in the one fire-box has been restored to proper condition.

Provided in the opposite side-walls 1, in the rear-end wall 2 and in the division wall 4 is a series of connected or communicating 85 flues 10 which are adapted to permit of a circulation of cold air by means of which said walls are maintained in a relatively cool condition, preventing the rapid destruction or deterioration of said walls which would 90 otherwise result due to the excessive heat to which they are subjected.

What is claimed is—

In a gas producer for furnaces, a pair of 95 side walls, a division wall between said walls and constituting with the latter fire-boxes, an arched crown extending over and supported centrally by said division wall and having its ends extending over the respective fire-boxes and supported by the respective side walls, a rear wall common to each of the fire-boxes and having a horizontal passage formed therein which passage extends across the rear end of the division wall and which has its ends communicating with 100 the respective fire-boxes, and terminating at 105

points central between the side and division walls, said crown forming the top wall which defines the top of said passage, and a passage extending from the horizontal passage and leading to the combustion chamber, the bottom walls of each of said passages being formed by the top of the rear wall, the passage leading to the combustion chamber

having a top wall supported by the top of the crown.

In testimony whereof, I affix my signature in presence of two subscribing witnesses.

WILLIAM O. HOUSTON.
